AUTOMATIC WINDOW CLEANING DEVICE

Harold M. Neal, 7054 Kelly St., Apt. 23, Pittsburgh, Pa.

Filed Dec. 6, 1957, Ser. No. 701,148

5 Claims. (Cl. 15—250.4)

This invention relates to window cleaning devices, and more particularly has reference to a power driven window cleaner, which will be designed for initiating and carrying to its conclusion a multi-stage, mechanical window-cleaning operation, responsive merely to the depression of a push button.

The advantages of a window cleaning device that will have the characteristics described above may be readily noted. The cleaning of windows is a comparatively expensive proposition, in various commercial enterprises in which there is a large number of windows to be cleaned. Large office buildings, for example, fall within this category, as do many factories, institutions, etc. Even in the home, the cleaning of windows is a disagreeable and difficult task, and accordingly, many home owners have utilized commercial window cleaning enterprises to clean the windows of their homes.

In view of the above, it is proposed to provide an automatic window cleaning device which will clean a window efficiently and swiftly, whenever desired, merely by operation of a push button. Thus, after the initial expense of installation of the device, further expenses in connection with the cleaning of windows, involving the use of labor, are dispensed with so that in a comparatively short time, the device in effect pays for itself.

Other object will appear from the following description, the claims appended thereto, and from the annexed drawing, in which like reference characters designate like parts throughout the several views, and wherein:

Figure 1 is a front elevational view of a window, showing fragmentarily a portion of a building in which the window is mounted, said window being equipped with a window cleaning device according to the present invention;

Figure 2 is an enlarged vertical, transverse section through the window, taken substantially on line 2—2 of Figure 1, portions being broken away;

Figure 3 is a vertical sectional view at right angles to the cutting plane of Figure 2, on the same scale as Figure 2, portions being broken away, taken substantially on line 3—3 of Figure 2;

Figure 4 is a transverse, vertical section on the same scale as Figure 2, taken substantially on line 4—4 of Figure 3;

Figure 5 is a vertical, transverse sectional view, on the same scale as Figure 2, taken substantially on line 5—5 of Figure 3;

Figure 6 is a horizontal section, on the same scale as Figure 2, taken substantially on line 6—6 of Figure 3;

Figure 7 is a vertical sectional view, on the same scale as Figure 2, taken substantially on line 7—7 of Figure 2, showing the water distribution manifold assembly;

Figures 8 and 9 are fragmentary sectional views, taken on the same cutting plane as Figure 2, showing in Figure 8 a swingable closure plate in a fully open position, as distinguished from Figure 2 in which said closure plate is in fully closed position, and showing in Figure 9 said closure plate in a partially closed position;

2

Figure 10 is a detail sectional view substantially on line 10—10 of Figure 8, showing the latch means for releasably holding the closure plate in open position;

Figure 11 is an elevational view of a fan incorporated in the construction for drying off excess water from the glass;

Figure 12 is a detail sectional view through the water supply control valve;

Figure 13 is a somewhat diagrammatic showing of the 10 wiring connections embodied in the invention; and

Figure 14 is a sectional view through a switch incorporated in the schematic showing of Figure 13, the switch being shown in its closed position as distinguished from Figure 13 wherein the switch is in open position.

Referring to the drawing in detail, the window incorporating the invention has been generally designated 20 and as shown in Figure 1, to the casual viewer shows no indication of the window cleaning mechanism thereof. Referring to Figure 6, the window is mounted in a window 20 opening 22 of a building wall 24. The invention includes vertical outer frame members 28, 30, at opposite sides of the window, fixedly mounted in positions extending transversely of and within the hollow interior of the building wall. Fixedly connected between the outer 25 frame members 30 are a lower, horizontal support plate or sill 32, and a horizontal lintel or header 34.

Extending vertically between the sill 32 and the header 34, in planes parallel to those of the frame members 28, 30 are inner frame members or jambs 36, 36, disposed 30 in closely spaced relation to the outer frame members 28, 30 so as to define at opposite sides of the window vertically extending cavities or chambers, for belt and pulley assemblies to be described hereinafter.

To rigidify the construction, spacer and brace means 35 may be employed, as shown in Figure 3. This means includes connecting bolts 40 extending across the chambers 41, 43 respectively defined at opposite sides of the window. The connecting bolts 40 extend through spacer sleeves 42.

40 Means is incorporated in the invention for supplying water to the window, and to this end there is a main water supply line or tube 44, extending within the building wall to a location immediately above the header 34. Tube 44, midway between the sides of the window, has a depending extension, with which branches 46 communicate, so that three outlets of the water supply conduit are provided, said outlets being disposed below the header 34 at the top of the window and being spaced apart transversely of the window as shown to best advantage in Figures 3 and 7.

50 The outlets of the main tube and branch tubes 44, 46 respectively are connected to a horizontally disposed manifold 48, extending transversely of the upper portion of the window and formed at closely spaced intervals over its full length with depending nozzles or outlets 50. Referring now to Figure 2, in which the cross sectional shape of the manifold is shown to particular advantage, it will be seen that the manifold has a first row of nozzles 50 disposed at one side of the plane of the window glass 52 that is to be cleaned. Another row of nozzles is disposed at the opposite side. The nozzles of each row are so angled as to direct water (and later, as will presently appear, jets of air) against the opposite faces of the window glass.

65 Thus, water distributed through the manifold will be caused to flow onto both faces of the glass, at all locations over the full width of the glass. Said water will of course flow downwardly over the opposite faces of the glass. Therefore, the entire area of the glass will be swiftly and uniformly covered with cleaning water.

70 Of course, it is desirable to provide means for draining off the water. To this end, a catch pan 54 is pro-

vided. This is of downwardly tapering formation as shown in Figure 3 with the flared top portion of the catch pan extending over the full width of the window, the lower end of the window extending into said top portion as shown clearly in Figure 2. The catch pan is progressively reduced in a downward direction, to cause all water flowing thereinto to gravitate to a centrally disposed outlet 56 of the catch pan, it being understood that a drain pipe 57 connected to said outlet would lead the water to a suitable location of disposal thereof.

At its top, the catch pan is flanged outwardly at opposite sides as shown in Figure 2, with the flanges thereof being fixedly secured to the underside of a support plate 58 slotted in registration with the catch pan to receive the lower end of the window and secured within a large opening 59 (Figure 3) formed in the sill 32.

Referring to Figure 3, at one side of the window a drive motor 60 is mounted upon a motor support ledge 61 fixedly secured to an extending between member 30 and an adjacent vertical member 63, within the building wall. Connected to shaft 62 of the motor for rotation therewith is a drive gear 64 in mesh (Figure 5) with a small diameter spur gear 66 rotatable with and driving the shaft of a fan assembly generally designated 68 mounted (Figure 5) upon a fan assembly support bracket 69 secured to ledge 61.

The output of the fan is directed into a small diameter tube 70 which extends, as shown in Figure 7, into one end of the conduit 48. It will be understood, in this connection, that a flap valve diagrammatically shown at 71, or equivalent check valve, would be provided where the tube 70 opens into the manifold 48, said valve opening in a direction to permit air to flow from tube 70 into the manifold, while preventing return flow. Said valve would normally close, so that when water is directed into the manifold, it would not flow toward the fan through the tube 70, the valve shutting off communication between the tube and manifold at this time. However, when the fan is placed in operation, the pressure of air within the tube 70 would shift the valve to open position, in which position it would remain as long as air is flowing into the manifold. Air directed into the manifold would find its outlet through nozzles 50, thus directing jets or blasts of air against both faces of the window glass for the purpose of drying off excess water following the application of water and the wiping of the same from the window glass.

Within chamber 43, there are provided two vertically extending belt and pulley assemblies, disposed in transversely spaced, parallel relation as shown in Figure 4. One assembly includes an upper pulley 72, endless belts 74 trained thereabout, and a lower pulley 76 about which the belt is also trained, the upper pulley being secured to the motor shaft for rotation therewith and the lower pulley being mounted upon a stub shaft carried by a support bracket 78 (Figure 3).

The other belt and pulley assembly includes upper pulley 80 secured to shaft 82 for rotation therewith, belt 84, and lower pulley 86.

Referring to Figure 6 and also to Figure 3, similar belt and pulley assemblies are in the chamber 41 at the other side of the window. Thus, one of said assemblies is in confronting relation to the first assembly and includes lower pulley 88, belt 90, and upper pulley 92. Pulley 92 is secured to the motor shaft 62, which as shown in Figure 2 extends completely across the window and is journaled, in chamber 41, in a bearing 93 mounted upon member 28.

The other belt and pulley assembly includes upper and lower pulleys 94 about which a belt 96 is trained, the upper pulley 94 being secured to the shaft 82 for rotation therewith. Therefore, in operation of the motor, all four belt and pulley assemblies will be driven, simultaneously and in the same direction.

Fixedly secured to the belts 74, 84 (see Figure 4) are

5
10
15

clamping brackets 98, 100 respectively. These have openings receiving non-circular ends of wiping blade support bars 102, 104 respectively, which bars may be fixedly engaged with the brackets by set screws of the clamps or by any equivalent means.

The bars 102, 104 extend fully across the window, and are engaged within chamber 41 fixedly in clamps 98, 100 corresponding to the first named clamps 98, 100 and mounted upon the belts 90, 96.

10 Referring to Figure 2, fixedly secured to support bars 102, 104 are elongated wiper blade clamp plates 106, 108 in which are clamped correspondingly elongated rubber wiping blades or squeegees 110, 112. Blades 110, 112 are so angled that when drawn along the opposite faces of the window pane, they will be set obliquely to the plane of the glass with their glass-contacting, beveled edges being the trailing edges of the blade and wiping off the water from the faces of the glass.

It will be noted in Figure 2 that the blades are oppositely angled. This is due to the fact that the belts at each side of the window turn in opposite directions, due to the fact that the rotational movement thereof is imparted by the oppositely rotating, meshing gears 64, 80 shown in Figure 5.

20 25 To guide the wiping blade assemblies in their movement, rollers 114 are rotatably mounted upon the respective wiper blade support bars, and referring now to Figure 6, said rollers are rotatably engaged in endless trackways 116, 118 formed in the side jambs 36, 36, said trackways following closely the paths in which the endless belts extend.

30 35 In Figure 2, it will be seen that normally, when the device is not in operation, all the portions or components thereof mounted within the top portion of the window assembly are concealed from view, by coplanar, horizontal closure plates 120 pivoted on pins 122 mounted in the respective side jambs. The plates 120 swing through ninety degrees between the full and dotted line positions shown for the left hand plate 120 in Figure 2. When in closed position, they abut opposite faces of the window glass, with the glass projecting upwardly above the closure plates.

40 45 50 As will be noted from Figures 8 and 9, the plates will normally remain in their closed positions due to the fact that curved arms 124 provided on the top surfaces of the plates will be engaged by the bars 102, 104. Arms 124 are of springable material, normally extending into the path of the bars so that when the bars move into engagement with the arms 124 they will swing the closure plates upwardly from the full open position shown in Figure 8, in the manner shown in Figure 9.

55 60 65 In other words, the bar 104 is traveling clockwise in Figures 8 and 9. As it travels clockwise, it of course moves the wiping blade over the window, to clean the window. Then, as it nears the end of its cycle, it engages the arm 124 which is now positioned as in Figure 8. Further upward movement of the bar 104 to the Figure 9 position will begin to swing the closure plate upwardly. Finally, bar 104 reaches the Figure 2 position, with a lug on said bar engaging the arm 124 to hold the closure plate in fully closed position. On the next cycle of operation, bar 104 will start moving clockwise from its Figure 2 position. Arm 124 will initially resist said movement, but will not have a spring tension strong enough to prevent the bar 104 from beginning its travel so that bar 104 causes the arm 124 to be temporarily tensioned, until the bar 104 disengages the arm. The bar 104 travels clockwise in the manner already described with reference to Figures 8 and 9, with closure plate 120 dropping automatically to its open position shown in dotted lines for the left hand plate 120 in Figure 2 and in full lines in Figure 8.

70 75 When the closure plate swings to its full open position, it is automatically latched in open position by a spring latch 126 (Figures 8-10), engaging plate 120 at each end

thereof. The tension of the latch is overcome by the plate gravitating to its open position to effect the latching action. However, the tension of the latch is readily overcome when the plate is being swung upwardly to its full closed position by the bar 102 or 104, as the case may be.

Considering now the wiring of the device, reference should be had to Figures 3 and 13. Leads 128, 130 extend from a suitable source of electric power, such as an ordinary 110 volt A.C. supply. A switch 132 shown to particular advantage in Figure 13 is provided, and from one terminal of said switch extends a lead 134, connected as shown in Figure 13 to one terminal of motor 60. From the same terminal of motor 60 extends a lead 136, connected to one contact or terminal 137 of a cut-off switch 138 mounted in the upper end of the chamber 43.

A lead 140 is connected, as for example by a jumper, to a pivoted contact blade 142 swingable under the bias of an associated spring 143 to a position (see Figure 14) engaging contact 137. Bar 102 temporarily biases blade 142 to a contact-opening, Figure 13 position as it passes by the same.

Lead 140 is connected to a fixed contact 148 of switch 132. A manually depressible, spring-loaded push button 144 is normally biased by its spring 146 to a position spacing a contact 150 from contact 148.

Extending from contact 148 is a lead 152 connected to lead 128. A lead 154 extends from the other terminal of motor 154 to lead 130.

A valve 156 for the water supply (see Figures 3 and 12) includes a plug 158 turnable between flow permitting and preventing positions by a handle 160.

Operation

On manual opening of valve 156, water under pressure flows through supply tube 44, branches 46, and nozzles 50 onto both faces of pane 52, draining therefrom into catch pan 54. The valve is then manually closed when the window is sufficiently wetted.

Push button 144 is now depressed and held down for a few moments. Current flows through lead 128; lead 152; closed contacts 148, 150; lead 134; motor 60; and return through leads 154 and 130.

The motor, driving the gears 64, 80, 66, now causes operation of the fan, and also initiates travel of the belts 74, 84, 90, and 96. Bar 102, travelling with belt 74, thus moves from its Figure 13 position. Contacts 142, 137 are therefore free to close, and do so as shown in Figure 14. Switch 138 thus closes almost immediately after depression of the push button. The operator therefore may now release the push button, since the circuit through the motor will remain closed. The current flow is now from lead 128; through lead 140; closed contacts 142, 137; lead 136; motor 60; lead 154; and return through lead 130.

As the motor continues operation, the wiping blades or squeegees 110, 112 are wiped across the opposite surfaces of the glass 52. Both blades travel downwardly during their wiping contact; then upwardly after moving laterally outwardly in opposite directions from the lower end of the glass (see Figure 2). The water is thus wiped off; meanwhile, to insure speedy removal of all the excess water, air is being blown downwardly by the fan onto both surfaces of the glass, emanating from the nozzles 51.

When the blades have made one full cycle, they are stopped in their initial position by engagement of bar 102 with blade 142. This swings blade 142 to its Figure 13 position, opening the circuit to the motor.

When the motor initially began operating, closure plates 120 were in their closed, Figure 2 positions. However, they were immediately disengaged from bars 102, 104 in the manner previously described herein, and dropped to open position before the wiper blade assemblies reached them during the downward movement of said assemblies.

Then, the bars 102, 104 engaged arms 124 of the now open closure plates, while the bars were moving upwardly and nearing their uppermost or rest positions shown in Figure 2. Therefore as the wiper blade assemblies moved above the closure plates at the end of the cycle, they pulled the closure plates upwardly behind them, to the normal, closed position of the closure plates.

It is believed apparent that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles, it being considered that the invention comprehends any minor change in construction that may be permitted within the scope of the appended claims.

What is claimed is:

1. A cleaning device for a window of the type including a frame structure and a window glass therein, comprising: means adapted to be mounted upon said structure for directing a cleaning fluid against the opposite surfaces of said glass; means for directing air currents against said surfaces following flowing of the fluid thereover; means adapted for mounting on said structure for wiping the fluid from said glass following direction of the fluid against said surfaces, comprising a pair of belt-and-pulley assemblies mountable on said structure at each side of the glass, a wiping blade carried by and extending between corresponding assemblies across the glass, means for driving the several assemblies simultaneously, said drive means including a drive motor and a gear train driven by said motor and having a driving connection with said assemblies; and closure plates 20 mountable on said structure at the top of the glass for movement between open and closed positions, said plates normally concealing said wiping blades, said fluid-wiping means engaging said closure plates to shift the same between open and closed positions.
2. A cleaning device for a window of the type including a frame structure and a window glass therein, comprising: means adapted to be mounted upon said structure for directing a cleaning fluid against the opposite surfaces of said glass; means for directing air currents against said surfaces following flowing of the fluid thereover; means adapted for mounting on said structure for wiping the fluid from said glass following direction of the fluid against said surfaces, comprising a pair of belt-and-pulley assemblies mountable on said structure at each side of the glass, a wiping blade carried by and extending between corresponding assemblies across the glass, means for driving the several assemblies simultaneously, said drive means including a drive motor and a gear train driven by said motor and having a driving connection with said assemblies; and closure plates 25 mountable on said structure at the top of the glass for movement between open and closed positions, said plates normally concealing said wiping blades, said fluid-wiping means engaging said closure plates to shift the same between open and closed positions.
3. A device for cleaning a window of the type including a frame and a window glass therein, comprising: 30 pulleys adapted for mounting on the frame adjacent the top and bottom edges of the glass; a belt trained about the pulleys; means mountable in the frame for driving at least one of the pulleys; a wiper means carried by the belt and disposed for moving between the top and bottom of the glass in wiping contact therewith responsive to driving of said one pulley; switch means controlling operation of the drive means and engaged by the wiper means when the wiper means moves to the top of the glass, said switch means operating to deenergize the 35 drive means when engaged by the wiper means; and a
4. A device for cleaning a window of the type including a frame and a window glass therein, comprising: pulleys adapted for mounting on the frame adjacent the top and bottom edges of the glass; a belt trained about the pulleys; means mountable in the frame for driving at least one of the pulleys; a wiper means carried by the belt and disposed for moving between the top and bottom of the glass in wiping contact therewith responsive to driving of said one pulley; switch means controlling operation of the drive means and engaged by the wiper means when the wiper means moves to the top of the glass, said switch means operating to deenergize the 40 drive means when engaged by the wiper means; and a
5. A device for cleaning a window of the type including a frame and a window glass therein, comprising: pulleys adapted for mounting on the frame adjacent the top and bottom edges of the glass; a belt trained about the pulleys; means mountable in the frame for driving at least one of the pulleys; a wiper means carried by the belt and disposed for moving between the top and bottom of the glass in wiping contact therewith responsive to driving of said one pulley; switch means controlling operation of the drive means and engaged by the wiper means when the wiper means moves to the top of the glass, said switch means operating to deenergize the 45 drive means when engaged by the wiper means; and a
6. A device for cleaning a window of the type including a frame and a window glass therein, comprising: pulleys adapted for mounting on the frame adjacent the top and bottom edges of the glass; a belt trained about the pulleys; means mountable in the frame for driving at least one of the pulleys; a wiper means carried by the belt and disposed for moving between the top and bottom of the glass in wiping contact therewith responsive to driving of said one pulley; switch means controlling operation of the drive means and engaged by the wiper means when the wiper means moves to the top of the glass, said switch means operating to deenergize the 50 drive means when engaged by the wiper means; and a
7. A device for cleaning a window of the type including a frame and a window glass therein, comprising: pulleys adapted for mounting on the frame adjacent the top and bottom edges of the glass; a belt trained about the pulleys; means mountable in the frame for driving at least one of the pulleys; a wiper means carried by the belt and disposed for moving between the top and bottom of the glass in wiping contact therewith responsive to driving of said one pulley; switch means controlling operation of the drive means and engaged by the wiper means when the wiper means moves to the top of the glass, said switch means operating to deenergize the 55 drive means when engaged by the wiper means; and a
8. A device for cleaning a window of the type including a frame and a window glass therein, comprising: pulleys adapted for mounting on the frame adjacent the top and bottom edges of the glass; a belt trained about the pulleys; means mountable in the frame for driving at least one of the pulleys; a wiper means carried by the belt and disposed for moving between the top and bottom of the glass in wiping contact therewith responsive to driving of said one pulley; switch means controlling operation of the drive means and engaged by the wiper means when the wiper means moves to the top of the glass, said switch means operating to deenergize the 60 drive means when engaged by the wiper means; and a
9. A device for cleaning a window of the type including a frame and a window glass therein, comprising: pulleys adapted for mounting on the frame adjacent the top and bottom edges of the glass; a belt trained about the pulleys; means mountable in the frame for driving at least one of the pulleys; a wiper means carried by the belt and disposed for moving between the top and bottom of the glass in wiping contact therewith responsive to driving of said one pulley; switch means controlling operation of the drive means and engaged by the wiper means when the wiper means moves to the top of the glass, said switch means operating to deenergize the 65 drive means when engaged by the wiper means; and a
10. A device for cleaning a window of the type including a frame and a window glass therein, comprising: pulleys adapted for mounting on the frame adjacent the top and bottom edges of the glass; a belt trained about the pulleys; means mountable in the frame for driving at least one of the pulleys; a wiper means carried by the belt and disposed for moving between the top and bottom of the glass in wiping contact therewith responsive to driving of said one pulley; switch means controlling operation of the drive means and engaged by the wiper means when the wiper means moves to the top of the glass, said switch means operating to deenergize the 70 drive means when engaged by the wiper means; and a
11. A device for cleaning a window of the type including a frame and a window glass therein, comprising: pulleys adapted for mounting on the frame adjacent the top and bottom edges of the glass; a belt trained about the pulleys; means mountable in the frame for driving at least one of the pulleys; a wiper means carried by the belt and disposed for moving between the top and bottom of the glass in wiping contact therewith responsive to driving of said one pulley; switch means controlling operation of the drive means and engaged by the wiper means when the wiper means moves to the top of the glass, said switch means operating to deenergize the 75 drive means when engaged by the wiper means; and a

closure plate adapted to be pivotally mounted on the frame adjacent the top edge of the glass for swinging movement to and from a horizontal position underlying and concealing the wiper means when the wiper means is disposed adjacent the top edge of the glass, said closure plate including a lateral projection positioned to be engaged by the wiper means as the wiper means approaches its switch-operating position, said projection being adapted to be moved by the wiper means to and retained by the wiper means in a position in which the closure plate will be disposed in said horizontal position thereof. 10

4. A device for cleaning a window of the type including a frame and a window glass therein, comprising: pulleys adapted for mounting on the frame adjacent the top and bottom edges of the glass; a belt trained about the pulleys; means mountable in the frame for driving at least one of the pulleys; a wiper means carried by the belt and disposed for moving between the top and bottom of the glass in wiping contact therewith responsive to driving of said one pulley; switch means controlling operation of the drive means and engaged by the wiper means when the wiper means moves to the top of the glass, said switch means operating to deenergize the drive means when engaged by the wiper means; and a closure plate adapted to be pivotally mounted on the frame adjacent the top edge of the glass for swinging movement to and from a horizontal position underlying and concealing the wiper means when the wiper means is disposed adjacent the top edge of the glass, said closure plate including a lateral projection positioned to be engaged by the wiper means as the wiper means approaches its switch-operating position, said projection being adapted to be moved by the wiper means to and retained by the wiper means in a position in which the closure plate will be disposed in said horizontal position thereof, said projection extending obliquely to the path of movement of the wiper means and being formed as a downwardly opening, curved hook in the open closure plate position, the wiper means being formed to exert a cam action on said hook tending to bias the same through substantially 40 90° to shift the closure plate to said horizontal position thereof, said hook remaining in engagement with the wiper means in the switch-operating position of the wiper means to retain the closure plate in its horizontal position. 45

5. A device for cleaning a window of the type including a frame and a window glass therein, comprising: pulleys adapted for mounting on the frame adjacent the top and bottom edges of the glass; a belt trained

about the pulleys; means mountable in the frame for driving at least one of the pulleys; a wiper means carried by the belt and disposed for moving between the top and bottom of the glass in wiping contact therewith responsive to driving of said one pulley; switch means controlling operation of the drive means and engaged by the wiper means when the wiper means moves to the top of the glass, said switch means operating to deenergize the drive means when engaged by the wiper means; and a closure plate adapted to be pivotally mounted on the frame adjacent the top edge of the glass for swinging movement to and from a horizontal position underlying and concealing the wiper means when the wiper means is disposed adjacent the top edge of the glass, said closure plate including a lateral projection positioned to be engaged by the wiper means as the wiper means approaches its switch-operating position, said projection being adapted to be moved by the wiper means to and retained by the wiper means in a position in which the closure plate will be disposed in said horizontal position thereof, said projection extending obliquely to the path of movement of the wiper means and being formed as a downwardly opening, curved hook in the open closure plate position, the wiper means being formed to exert a cam action on said hook tending to bias the same through substantially 20 90° to shift the closure plate to said horizontal position thereof, said hook remaining in engagement with the wiper means in the switch-operating position of the wiper means to retain the closure plate in its horizontal position, the closure plate being mounted for free gravitational swinging movement to a vertical open position on disengagement of the hook from the wiper means. 25 30 35
